UNITED STATES PATENT OFFICE.

ELMER A. TERPENING, OF GENESEO, ILLINOIS, ASSIGNOR OF ONE-HALF TO
HARRY HOUSTON CLARKE, OF NEW YORK, N. Y.

WEIGHING-SCALE.

SPECIFICATION forming part of Letters Patent No. 595,502, dated December 14, 1897.

Application filed October 3, 1896. Serial No. 607,749. (No model.)

To all whom it may concern:

Be it known that I, ELMER A. TERPENING, of Geneseo, in the county of Henry and State of Illinois, have invented a new and Improved 5 Weighing-Scale, of which the following is a full, clear, and exact description.

The object of the invention is to provide a new and improved weighing-scale, more especially designed for weighing ice, cotton-bales, 10 and other merchandise while in motion.

The invention consists principally of a pulley adapted to be rotated from the weighing-beams, a clutch mechanism for actuating the tally or registering device and adapted to engage 15 the said pulley, and a tripping device controlled by the merchandise for throwing the clutch mechanism out of engagement with the said pulley.

The invention also consists of certain parts 20 and details and combinations of the same, as will be fully described hereinafter and then pointed out in the claims.

Reference is to be had to the accompanying drawings, forming a part of this specification, 25 in which similar characters of reference indicate corresponding parts in all the figures.

Figure 1 is a side elevation of the improvement with part in section. Fig. 2 is a plan view of the same with part broken out. Fig. 30 3 is an enlarged transverse section of part of the improvement. Fig. 4 is an enlarged sectional side elevation of the tally or registering device and adjacent parts. Fig. 5 is a sectional plan view of the same, and Fig. 6 is a 35 face view of the registering device.

The improved weighing-scale is provided with a suitably-constructed frame A, in which is arranged a platform B, adapted to receive merchandise from a chute or like device, so 40 that the merchandise slides over and off the platform B in the direction of the arrow a'. The platform B is hung on weighing-beams D, connected at their inner free ends with the head E' of a rod E, extending through a 45 tube F' into a box F, secured on the frame A and containing oil or other liquid.

The inner or lower end of the rod E is connected with a scale-spring G, attached at its lower end to the piston H of a dash-pot I, supported 50 by rods I' and a cross-head I² from the said rod E. The downwardly-extending pis-

ton-rod H' of the piston H is secured at its lower end to the bottom of the box F.

When a block of ice, a bale of cotton, or other merchandise slides over the platform 55 B, then the weight of said merchandise causes the platform B to move downward and actuate the beams D, so as to move the head E' and rod E in an upward direction against the tension of the scale-spring G. The dash-pot 60 I moves with the rod E, and the said dash-pot and piston H serve to take up all shock and jar incident to the merchandise passing over the platform.

From the lower end of the rod E extends 65 an arm E², connected with a cord, rope, or wire J, winding around a pulley K and connected at its lower end with a spring J', secured on the dash-pot I. The pulley K is journaled in suitable bearings held in the box 70 F, and one face of the said pulley is adapted to be engaged by a clutch-wheel L, mounted to rotate loosely on the bearing for the shaft of the pulley K, as indicated in Fig. 3. The clutch-wheel L is connected with the tally or 75 registering device N to actuate the same, so as to register the weight of the merchandise that passes over the platform B.

The mechanism connecting the registering device or tally N with the scale-spring 80 G is so proportioned that the weight or load passing over the platform and expanding the said spring is indicated in pounds or like measurement of weight by the tally. The expansion of the spring G corresponds to the 85 upward movement of the rod E, and the distance the latter moves causes the pulley K and clutch-wheel to turn a corresponding distance, and as the clutch-wheel actuates the registering device proportionately it is evident that it indicates the amount of the weight 90 of the load passing over the platform B.

The construction of the registering device N (shown in detail in Figs. 4, 5, and 6) is as follows: A transverse shaft N' is journaled in 95 the casing N², and on the rear end of the said shaft is secured a star-wheel N³, adapted to be turned by equidistant projections L' on the front face of the clutch-wheel L. On the shaft N', within the casing N², is secured a 100 pinion N⁴, in mesh with a gear-wheel N⁵, mounted to rotate loosely on the shaft N' and

carrying on its face a pin or stud N⁷, provided with a pointer N⁸, indicating on the dial N⁹, fixed in the casing N². The several parts are so proportioned that a whole revolution of 5 the clutch-wheel L imparts a full revolution to the star-wheel N³ and pinion N⁴, so that the gear-wheel N⁵ is turned to move the pointer N⁸ a distance on the fixed dial N⁹ to indicate one hundred pounds, and if the 10 clutch-wheel makes but one-fifth of a revolution the gear-wheel is turned to move the pointer N⁸ over the dial N⁹ to indicate twenty pounds. As shown, the number of arms on the star-wheel N³ correspond to the number 15 of projections L' on the clutch-wheel, and the dial is graduated to record a minimum weight of twenty pounds; but it is evident that the several parts can be so proportioned and arranged that any desired amount in weight 20 measure can be registered by the tally N. The dial N⁹ is secured on the stud N⁶ and is graduated up to two thousand pounds or one ton. The pin N⁷ on every revolution meshes into and turns the wheel N¹⁰, held on the stud 25 N¹¹ and carrying the unit-ton wheel N¹², read through an opening in the fixed dial N⁹, as shown in Fig. 6. A pin N¹³ on the wheel N¹⁰ turns on each revolution of the latter. A wheel N¹⁴, mounted to rotate loosely on the 30 stud N⁶ and carrying the tens-of-tons wheel N¹⁵, is likewise read through an opening in the dial N⁹. A pin N¹⁶ on the hub of the wheels N¹⁴ N¹⁵ serves to rotate the wheel N¹⁷, carrying the hundreds-of-tons wheel N¹⁸. 35 Thus, as shown in Fig. 6, the aggregate weight of the loads that have passed over the platform B is one hundred and sixty-one tons.

The clutch-wheel L is fitted to slide on its bearing and is engaged by a shifting arm O, 40 secured on a vertically-disposed shaft O', journaled in suitable bearings in the box F and passing through a tube F² therein, as indicated in Fig. 1.

On the upper end of the shaft O' is secured 45 an arm O², drawn on by a spring O³, so as to normally hold the clutch-wheel L in mesh with the face of the pulley K, so that when the latter is rotated a rotary motion is given to the wheel L, and the motion of the latter 50 is transmitted to the registering device N to indicate the proper weight of the merchandise that passes over the platform B.

In order to throw the clutch-wheel out of engagement with the pulley K, I provide the 55 following device, controlled from the merchandise C as the latter passes over the end of the platform B: The arm O², previously mentioned, is pivotally connected by a link P with an arm P', secured on a shaft Q, journaled in the frame A near the exit for the merchandise C, as shown in Figs. 1 and 2. The shaft Q carries a tripping-lever R, which extends down into the path of the merchandise C, so that when the latter moves off the 60 platform it imparts an upward-swinging motion to the said lever R, whereby the shaft Q is rotated and the arm P', the link P, and

arm O² impart a rotary motion to the shaft O', so that the shifting arm O moves the friction-wheel L out of engagement with the pulley K. As soon as the merchandise C has passed over the platform the lever R returns to its former position by swinging downward, and the spring O³, acting on the arm O², causes a turning of the shaft O' to cause the 75 arm O to move the friction-wheel L back into engagement with the pulley K.

Now it will be seen that by the arrangement described the merchandise passing over the 80 platform B is weighed and the mechanism is reset upon the merchandise leaving the platform, so that the scale is ready for weighing a second piece of merchandise delivered to and passing over the platform B, as above 85 described.

The tubes F' and F² for the rod E and shaft O' prevent the liquid contained in the box F from escaping in case the weighing-scale is tilted while being shifted from one place to another. It is understood that the spring G 90 always returns the pulley K to its previous position as soon as the merchandise slides over the platform B and previous to the clutch-wheel again engaging the said pulley K.

It will also be seen that by the arrangement 95 described the machine is self-adjusting or balancing, so that an accumulation of dirt or pieces of merchandise does not affect the proper weighing of the merchandise passed over the platform B.

Having thus fully described my invention, I claim as new and desire to secure by Letters Patent—

1. A weighing-scale, provided with a pulley 105 adapted to be turned from the weighing-beams, a registering device, a clutch mechanism for actuating the registering device from said pulley, and a tripping device controlled by the merchandise, for throwing the clutch mechanism out of engagement with the said pulley, substantially as shown and described.

2. A weighing-scale, comprising a platform, 115 weighing-beams carrying the said platform, a spring-pressed rod connected with the said beams, a rope and pulley connected with the said rod for turning the pulley, upon the beams being actuated by the merchandise passing over the platform and a registering device operated from said pulley, substantially as shown and described.

3. A weighing-scale, comprising a platform, 125 weighing-beams carrying the said platform, a spring-pressed rod connected with the said beams, a rope and pulley connected with the said rod for turning the pulley, upon the beams being actuated by the merchandise passing over the platform, a weight-registering device, a clutch mechanism adapted to engage the said pulley and adapted to actuate the registering device, and a tripping-lever in the 130 path of the merchandise as the latter leaves the platform, the said tripping-lever controlling the said clutch mechanism, substantially as shown and described.

4. A weighing-scale, provided with a rod connected with the weighing-beams supporting the platform, a spring connected with the said rod and attached to a dash-pot piston, a 5 spring-pressed cord carried by the said rod, a pulley engaged by the said cord, and a clutch mechanism for actuating the registering device, and adapted to engage the said pulley to be rotated by the latter, substantially as 10 shown and described.

5. A weighing-scale, provided with a rod connected with the weighing-beam supporting the platform, a spring connected with the said rod, a dash-pot having its piston connected to said spring, a spring-controlled cord carried by the same rod, a pulley engaged by the said cord, a registering device engageable with said pulley to be rotated thereby, and a tripping-lever in the path of the merchandise 15 actuated to disconnect the pulley and registering mechanism by the passage of the merchandise, substantially as described.

6. A weighing-scale provided with a weighing-platform, a registering device, operative 20 connections between the platform and registering device, and a tripping device controlled by the merchandise passing over the platform and temporarily breaking said operative connections, substantially as shown and described.

7. A weighing-scale provided with a weighing-platform, a registering device normally connected to move with the said platform, and a tripping device controlled by the merchandise passing over the said platform and serving to release the said registering device, substantially as shown and described.

8. A weighing-scale provided with a rod connected with the weighing-beam supporting 25 the platform, a spring connected with the said rod, a dash-pot having its piston connected to said spring, a spring-controlled cord carried by the said rod, a pulley engaged by

the cord, a registering device, a clutch mechanism normally connecting the pulley and registering device, and a tripping-lever in the path of the merchandise actuated by the passage of the merchandise, and connections from said lever to the clutch for disengaging it from the registering mechanism, substantially as described.

9. A weighing-scale, having a registering device controlled jointly by a spring and the weight of the article being weighed, said spring, and means for automatically breaking the operative connection to said registering device by the removal of the article from the scale, substantially as described.

10. A weight-registering device for scales, comprising a member having a forward and return movement and operated by depression of the scales, a cumulative indicator operated thereby, and means for automatically releasing the same during its return movement by the removal of the article from the scale, substantially as described.

11. A weighing-scale provided with a cumulative registering device normally connected to the weighing mechanism, and a tripping device actuated by the article passing over the scale to disconnect the registering device as the article leaves the scale, substantially as described.

12. A weighing-scale provided with a registering device normally connected to the weighing mechanism, and a tripping device actuated by the article in passing over the scale, to temporarily disconnect the registering device as the article leaves the scale, whereby the registration becomes cumulative, substantially as described.
